CLAIM

We claim the ornamental design for an educational grain-stuffed doll with wrist tag identifying type of grain visible through transparent chest window, as shown and described.

DESCRIPTION

FIG. 1 is a perspective view of an educational grain-stuffed doll with wrist tag identifying type of grain visible through transparent chest window showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The view of FIG. 1 shows a window flap thereof in an opened condition whereas all other views show the window flap in a closed condition.
